UNITED STATES PATENT OFFICE

WILLIAM JOHNSON, OF CHICAGO, ILLINOIS

HOUSEHOLD TOOL

Application filed October 16, 1929. Serial No. 399,909.

This invention relates to improvements in household tools, and primarily to a bottle opener designed for the drawing of corks or for the removal of crown caps from bottles, and is also adapted to be used in the sewing up of fowl or the roasts of meat, and for other similar purposes.

The object of the invention is to so construct the tool that it may be cheaply stamped from a single sheet of comparatively thin metal and at the same time possess the necessary stiffness and rigidity to subserve the ends in view.

Other objects will appear from a detailed description of the invention, in conjunction with the accompanying drawings, wherein,—

Figure 1 is a side elevation of what may be termed the front side of the tool;

Fig. 2 is a side view of the rear of the tool; Fig. 3 is a cross sectional view taken on line 3—3 of Fig. 1; and

Fig. 4 is a cross sectional view taken on line 4—4 of Fig. 1;

Fig. 5 is a cross sectional view taken on line 5—5 of Fig. 1.

The tool is stamped from a single sheet of metal, and is formed to afford a stem 10 terminating at its lower end in a barb 11. The material at the upper end of the stem is spread laterally to afford a widened shank 12 which at its upper end broadens out into a loop-shaped handle 13 provided with an aperture 14, the lower edge of which is formed with a web 15 which in conjunction with the upper edge 16 serves to afford means for the prying off of crown caps.

In order to afford the necessary rigidity of structure, the metal is configured to afford a marginal bead 16 around the upper and side portions of the loop at the upper end of the tool, and these marginal beads converge in the shank portion 12 to provide closely adjacent corrugations 17 separated by a center groove 18. This center groove, which spaces the beads 17, terminates near the lower end of the shank at the point 19, and from that point downwardly the metal converges into the stem which is of channel formation, as in Fig. 4.

The channel terminates at the point where

the metal of the stem merges into the barb 11, and the upper shoulder portion of the barb is provided with a small notch 20.

It will be understood that the under or reverse face of the tool as illustrated in Fig. 2 presents the complementary formation throughout.

The web 15 and the metal contiguous to the opposed edge 16 lies in a flat plane, so that an upper narrow rim or lip is opposed by the web which provides for engagement with the edges of a crown seal. The channel 21 formed within the stem affords a duct or vent passage for the escape of gas from corked bottles containing charged beverages, which arrangement permits the barb to be forced downwardly alongside of the cork until the barb passes below the lower end of the cork, after which the tool may be turned to bring the shoulder of the barb into transverse relation with the lower end of the cork, which permits the cork to be withdrawn and also affords escape for the gas from the bottle during the operation of removing the cork. In this operation, the upper looped end of the tool affords a convenient handle through which the finger may be thrust in using the implement.

When the device is used for the removal of crown caps, the shank end serves as a handle.

When the device is used for sewing fowl or meat, the barb serves to pierce the flesh, after which a string or cord may be looped over the notched portion of the barb and drawn back in stitching up the fowl or meat.

The barb may also be used in the removal of milk bottle seals, and for various other purposes, and in fact constitutes a household tool of diversified utility.

The invention may be cheaply constructed by simple operations, and possesses great rigidity, due to the beaded or corrugated configuration of the metal.

I claim:

1. A household tool comprising a shank portion of corrugated formation, the metal at the lower end of the shank being converged, and the edges thereof bent to U-shaped formation to afford a narrow grooved stem terminating at its lower end in a barb.

2. A household tool comprising a shank portion of corrugated formation, the metal at the lower end of the shank being converged, and the edges thereof bent to U-shaped formation to afford a narrow grooved stem terminating at its lower end in a barb provided with a notch in the shoulder thereof.
3. A household tool comprising a shank portion of corrugated formation, the metal at the lower end of the shank being converged, and the edges thereof bent to U-shaped formation to afford a narrow grooved stem terminating at its lower end in a barb, and the metal at the upper end of the shank being widened to afford a loop, the corrugations in the shank being carried upwardly around the loop to afford a marginal bead.
4. A household tool comprising a shank portion of corrugated formation, the metal at the lower end of the shank being converged, and the edges thereof bent to U-shaped formation to afford a narrow grooved stem terminating at its lower end in a barb provided with a notch in the shoulder thereof, and the metal at the upper end of the shank being widened to afford a loop, the corrugations in the shank being carried upwardly around the loop to afford a marginal bead.
5. A household tool comprising a shank portion of corrugated formation, the metal at the lower end of the shank being converged, and the edges thereof bent to U-shaped formation to afford a narrow grooved stem terminating at its lower end in a barb, and the metal at the upper end of the shank being widened to afford a loop, the corrugations in the shank being carried upwardly around the loop to afford a marginal bead, and the metal at the throat of the loop and intermediate the marginal bead portions being flattened to afford an intervening web adapted to engage a crown cap.
6. A household tool comprising a shank portion of corrugated formation, the metal at the lower end of the shank being converged, and the edges thereof bent to U-shaped formation to afford a narrow grooved stem terminating at its lower end in a barb provided with a notch in the shoulder thereof, and the metal at the upper end of the shank being widened to afford a loop, the corrugations in the shank being carried upwardly around the loop to afford a marginal bead, and the metal at the throat of the loop and intermediate the marginal bead portions being flattened to afford an intervening web adapted to engage a crown cap.

In witness that I claim the foregoing I have hereunto subscribed my name this 7th day of October, 1929.

WILLIAM JOHNSON.
